UNITED STATES PATENT OFFICE

2,268,807

AIRCRAFT FUEL PUMP

Russell R. Curtis, Dayton, Ohio, assignor to Curtis Pump Company, Dayton, Ohio, a corporation of Ohio

Original application July 13, 1939, Serial No. 284,263. Divided and this application March 8, 1941, Serial No. 382,315

3 Claims. (Cl. 103—42)

This invention is a division of my copending application, Serial No. 284,263, filed July 13, 1939, and relates to aircraft fuel pumps and more particularly to mechanism for maintaining at a constant value the pre-selected pressure on the discharge side of the pump.

Due to the fact that fuel tanks in aircraft are usually remotely located with respect to the fuel pump, it is inevitable that the various angles which the craft assumes in flying frequently alter the suction head on the intake side of the pump. Unless compensated for, this rise and fall in the suction head constantly influences the discharge pressure of the pump as regulated by the relief valve.

It is therefore an object of this invention to provide simple yet accurate compensating means whereby the negative loading of the relief valve due to increased suction on the low side will not affect the pressure on the discharge side for which the valve has been adjusted.

Another object of this invention is the provision of balancing means for a relief valve structure whereby variation in the suction does not add to or subtract from the forces tending to open the valve and therefore does not affect the discharge pressure of the fuel pump.

The novel features believed to be characteristic of the present invention are set forth with particularity in the appended claims. The invention itself, however, both as to its organization and manner of construction, together with further objects and advantages thereof, may best be understood by reference to the following description taken in connection with the accompanying drawing, in which:

Figure 1 is a vertical cross-sectional view, with parts in elevation, of a fuel pump, illustrating the details of construction of the diaphragm and valve spring cup when the latter is at its lowermost limit of movement as taught by the present invention;

Figure 2 is a transverse cross-sectional view taken substantially in the plane of the joint indicated by the broken line II—II of Figure 1;

Figure 3 is a fragmentary cross-sectional view of the diaphragm and valve spring cup arrangement similar to Figure 1 but showing the relation of parts when the cup is actuated to its uppermost limit of movement.

As best shown in Figure 1, the pump body 12 is bored intermediate its ends and concentrically supports the eccentrically bored pump cylinder 20 and is provided with front and rear journals

(not shown) for rotatively supporting a rotor 26. The rotor is transversely slotted to slidably receive the three through-blades 34, the cylinder bore and ends of the blades being so formed that the blade ends contact the cylinder wall at all points in their rotation.

The cylinder 20 has slots 36 and 38 positioned to align with ports 40 and 42 in the body 12.

With rotation in the direction of the arrow 44, Figure 1, 40 becomes the suction port and 42 the discharge port, but by merely removing the screws (not shown) that connect the valve body 106 to the pump body 12 and turning the entire relief and by-pass valve structure through an angle of 180° on its vertical axis and reconnecting the valve and pump bodies, the pump will be adapted for rotation in a direction opposite to that of the arrow 44, whereupon 42 is the suction port and 40 the discharge port. No other change is required. Opposite hubs 48 are pipe threaded as at 49 for suction or discharge pipes as required.

A suitable driving mechanism (not shown) is provided for driving connection with the rotor 26.

The relief valve structure provided for maintaining the discharge pressure at a constant value is housed in the valve body 106 which is suitably secured to the pump body by means of screws or the like, and a valve head 108 secured to the main valve body 106 by the screws 110.

The relief valve proper is of the poppet type comprising the disk 112 with stem 114 slidably in a hub 116 of the main body 106, the disk being beveled at 118 and having a corresponding angular seat in the body which divides the interior of the body 106 into a suction chamber 120 including all of the space above the disk 112 and a discharge chamber 122 below the disk.

Ducts 124 and 126 in the pump and valve bodies, respectively, connect the suction port 40 to the suction chamber 120, while ducts 128 and 130 in the valve body and pump body respectively connect the discharge chamber 122 to the discharge port 42.

Depending from the valve head 108 into the suction chamber 120 is a long hub 132 internally chambered to contain a valve loading spring 134 and externally sized to slidably receive a valve spring cup 136, the bottom of which rests upon a small knob 138 on the upper side of the valve disk 112.

The valve spring adjusting means comprises an adjusting screw 140 with a head 142 and a flange 144 intermediate the screw and head, the flange being of larger diameter than the head.

The lower adjusting screw retaining washer 146 rests on a shoulder 143 and has a central opening through which the screw extends freely, the flange 144 resting on the upper face of the washer. The upper retaining washer 150 has a central opening which passes over the screw head 162 loosely and rests on the flange 144. A spring ring 152 is snapped into a groove at the upper edge of the washer 150, the groove being positioned to hold the two washers so spaced as to allow free turning movement of the flange 144 between them. A spring adjusting nut is tapped to fit the external threads of the screw 140 and has a peripheral key extending laterally into a keyway (not shown) on the valve head 108, whereby the nut is held non-rotatable when the screw is turned, yet may move freely in an axial direction.

The head 142 of the adjusting screw is provided with a deep screwdriver slot 160 in which the locking bar 162 is fitted snugly and is hinged therein by the pin 165. The hole in the upper retaining washer 150 has a series of radial notches (not shown) into any one of which the lower edge of the locking bar 162 may be entered. The washer 150 also has a key at its outer edge (not shown) similar to the key on the spring adjusting nut 154 and which extends into a keyway in the valve head 108 to hold the washer 150 from rotating.

The adjusting screw cap 170 when drawn tightly to the gasket 172, allows but a slight clearance between the inside of the cap and the top of the locking bar 162 whereby the bar is retained in the notch in which it has been placed as long as the cap is in position.

When an adjustment of the spring 134 is to be made, the cap 170 is first removed, then, by the simple insertion of a screwdriver into the slot 160, the locking bar 162 is made to rise out of the notch in the washer 150 and the screw may be rotated until the desired adjustment is obtained, whereupon the locking bar is pushed into the nearest notch and the cap 170 replaced. In a situation where it may be necessary to reach into close spaces to make this adjustment, the desirability of this simple manipulation is obvious.

Furthermore, where height is limited, as it is on pumps of this class, a small portion only of the available height is taken by the adjusting and locking means, leaving space for a longer and more flexible spring, whereby larger increments of adjustment may be made with smaller resulting variations in spring stress making the matter of adjusting for fine variation in discharge pressure not dependent upon skillful or careful manipulation of the adjusting means. The use of a longer and more flexible spring also results in less variation in the discharge pressure at the various speeds of rotation and rate of discharge encountered in the operation of aircraft.

Now, as is well known in the art, the suction head against which the pump operates varies from one instant to the next because of aircraft acceleration, or deceleration, or altitude, or the fact that the fuel tank, when the aircraft climbs, may be well below the pump, and when it dives it may be well above it, or vice versa, all depending upon the respective locations of the pump and tank. Consequently, if an ordinary spring-loaded release valve only were provided, this changing rise and fall of the pressure in chamber 120 would cause the discharge pressure to fluctuate, because of the sum total of the force acting

against the spring to open the valve would be the discharge pressure, acting to raise the valve from below, plus the suction tending also to raise it but from above. Valves for use in this situation are therefore provided with a balancing means whereby variation in the suction does not add to nor subtract from the forces tending to open the valve, and therefore does not affect the discharge pressure. The release valve balancing means herein provided comprises a diaphragm 174 of resilient synthetic rubber preferably with an internal fabric layer (not shown) to give it additional strength. Around the edge of the central opening the material is thickened to provide a ring 176 around which the upper edge of the spring cup 136 is so closely rolled as to form an airtight joint at this point, and prevent the cup and diaphragm from pulling apart in operation.

The diaphragm is also made thicker at the outer edge to form the wedging ring 178, this ring and a small portion of the diaphragm being clamped between the valve body 106 and the valve head 108.

Since the material of the diaphragm is subject to cold flow under excessive pressure, the space between the body 106 and head 108, which contains the outer edge, must be carefully made so that when metal to metal contact of the body and head is made at 180, the diaphragm will be gripped tight enough to safely prevent pulling out under the suction pressure in operation, but not tight enough to cause cold flow.

The active portion 182 of the diaphragm is of U shaped cross section which loops downward between the outside of the cup 136 and the inner edge of the annular rib 184 in the body 106.

Since the material composing the diaphragm swells appreciably from gasoline absorption, the loop 182 will drop downward more as the material swells. It will also be drawn upwardly farther as the valve rises to its maximum height. If then, the effective area of the diaphragm is to remain constant under both of these extremes, the sides of the U loop must be so supported as to maintain a constant width under all conditions.

This condition will be met when the drop in the loop 182 and the width of the rib 184 is such that the sides of the loop will be held parallel and to a uniform spacing with each other in all positions. In such a structure, the effective area of the diaphragm will be constant for any valve lift and for any degree of swelling of the material, and the discharge pressure will be unaffected by these variations.

The relative positions of parts at the extreme limits of movement of the valve spring cup 136 are best illustrated in Figures 1 and 3. As shown in Figure 1, the valve spring cup 136 is at its lowermost limit of movement in which it rests on the knob 138 of the valve disk 112. In Figure 3, the valve spring cup 136 is illustrated as abutting the end of the chamber 186 in which it is in its uppermost limit of movement.

The diaphragm 174 is so shaped and positioned that the valve disk 112 may rise to its maximum operating height a distance of approximately $\frac{1}{32}$ of an inch without causing change in the effective area of the diaphragm. The loop 182 of the diaphragm remains exposed to the suction chamber 120 as the valve disk 112 is raised and lowered. As the valve spring cup 136 rises, it effects a rolling action of the diaphragm loop 182 in such a manner that the effective area thereof remains substantially constant.

The space forming the chamber 186 is usually connected by a hole 188 to the atmosphere, but may be connected to the intake manifold when a supercharger is employed, by a pipe fitted to the tapped opening 190, causing the fuel discharge pressure to increase directly with rise in manifold pressure.

Obviously, increased suction in the chamber 120 will pull as much harder downwardly on the cup 136 as it does upwardly on the valve disk 10 112, and the valve closing pressure will be controlled entirely by the spring 134 independently of variations in suction heads.

A by-pass valve is usually incorporated in the relief valve body of the power pump of aircraft fuel systems, so that, in the event of sticking of the power pump rotor, or other power pump failure, fuel may be forced through the power pump independently of its coupling elements, by means of an auxiliary hand pump provided for the purpose.

Heretofore, these by-pass valves have been made with a metal to metal seat, necessitating considerable initial spring pressure to hold them closed when not operating, and have not been so placed as to provide the greatest freedom in the passages through them, whereby considerable hand pump effort was required to overcome these innate resistances before hand pumping became effective.

The by-pass valve 192 herein disclosed is of synthetic rubber to metal seat construction so that a very light spring holds it closed effectively against leakage, and it is so placed and its orifices so shaped, as to provide a substantially direct non-resisting passage for the flow of the hand pumped fuel.

While the constructions of the locking arrangements for the adjustable spring, the rotary main pump and the by-pass valves have been described in more or less greater detail, it is to be understood that such constructions form no part of the invention claimed herein and are illustrated and described only for the purpose of more clearly defining their coaction in relation to the adjustable spring cup and diaphragm. Any other types of constructions which would coact with the adjustable spring cup and diaphragm in a like manner may be used equally as well.

While a particular embodiment only of this invention has been illustrated, it will, of course, be understood that the invention should not be limited thereto, since many modifications may be made and, therefore, it is contemplated by the appended claims to cover all such modifica-

tions as fall within the true spirit and scope of the present invention.

I claim as my invention:

1. A diaphragm construction comprising a pair of spaced relatively movable members, a flexible diaphragm extending between the members and having legs adapted to roll against one of the members and away from the other member as the members are moved relative to each other for maintaining the same exposed diaphragm area between the members for various relative positions of the members.

2. A diaphragm assembly comprising a housing having a cylindrical inner wall, a cylindrical cup member slidable in said housing in spaced relation from said inner wall, a flexible diaphragm surrounding said cup member and bridging the space between the member and housing, said diaphragm having inner and outer marginal portions adapted to engage the cup member and the cylindrical wall respectively and to roll from such engaging position into bridging position between the housing and cup whereby the effective exposed area of the diaphragm between the housing and cup remains constant for all positions of the cup in the housing while being defined by different portions of the diaphragm.

3. In a pump including a housing defining a suction chamber between the inlet and discharge sides of the pump in communication with the inlet side of the pump, a relief valve in said housing between said suction chamber and discharge side of the pump, and adjustable means for loading said relief valve, the improvements 35 which comprise said housing having a tubular portion depending in said suction chamber into spaced relation from said relief valve and said tubular portion being spaced from the walls of said housing, a cup member slidably embracing 40 said tubular portion and having a closed end between the adjustable loading means and the relief valve, said loading means urging the closed end of said cup against the relief valve, a flexible diaphragm surrounding said cup member and looped between the cup member and the housing 45 to bridge the space therebetween, said diaphragm having inner and outer marginal portions adapted to engage the cup member and the housing respectively and to roll from such engaging positions into bridging relation between the housing and cup member for maintaining the same exposed diaphragm area between the housing and cup member for various relative positions thereof.

RUSSELL R. CURTIS.
